STEPLADDER JOINT AND SHELF SUPPORT

Filed March 27, 1929

UNITED STATES PATENT OFFICE

SPENCER M. PETERS AND ARTHUR B. ROCHESTER, OF SPRINGFIELD, ILLINOIS; SAID ROCHESTER ASSIGNOR TO SAID PETERS

STEPLADDER JOINT AND SHELF SUPPORT

Application filed March 27, 1929. Serial No. 350,339.

Our invention relates to joint members, reinforcements and stepladder shelf supports adapted to be used at the top of a stepladder where the step ladder legs are joined to the 5 stiles; an object being in this device particularly to provide a substantial and durable connection between the step ladder legs and the stiles at their point of attachment and to provide in connection with a substantial joint 10 of this kind a means of pivotally supporting and substantially resting a pivoted top step ladder shelf at the upper end of the step ladder for convenience in use and economy in manufacture.

15 We attain the objects of our invention in the step ladder joint and shelf support hereinafter described and recited in the claims.

Referring to the drawings:

Fig. 1 is a perspective of the upper end of 20 a step ladder disclosing the joint and shelf support of our invention.

Fig. 2 is a vertical half-section taken through a portion of the upper end of a 25 step ladder showing in section a step ladder shelf and one of the step ladder steps.

Fig. 3 is a front view of a step ladder folded with the upper shelf pivotally folded down between the ladder stiles and showing in a 30 cut-away a more complete detail of the joint member and shelf support member.

Fig. 4 is a vertical half-section of what is 35 shown in Fig. 2 with the leg member folded in a closed position and the shelf member also pivotally folded between the stiles.

Fig. 5 is a vertical half-section of a leg and 40 stile of a step ladder disclosing the manner of securing the leg member to a stile member at the joint and disclosing the relative operating position of the joint member and shelf support member.

Fig. 6 is a perspective of the step ladder joint and shelf support plate disclosing in 45 dotted lines the manner in which the shelf operatively rests on a stop member of a hinged plate.

Fig. 7 is a perspective of a U shaped plate used for re-enforcing the pivotal connection of the step ladder legs with the step ladder stiles at their pivotal connecting point.

50 Referring in detail to the structure of our

step ladder joint and shelf support we provide at the top of stiles —1— and —2— joint plates —3— and —4— substantially engaging the upper end of the stiles. These plates have integral front and rear flanges —5— and —6— —7— and —8— (not shown) adapted to respectively engage the front and rear face of the top of the stiles while each of these plates —3— and —4— have the upper portion of flanges —7— and —8— (not shown) inwardly bent in the same plane with the flange and in opposite directions therefrom in a relative position to provide a substantial shelf support —9— and —10— for the operative support of step ladder shelf —11— hingedly supported pivotally on a rod —12—. This shelf is re-enforced by angle bars —13— and —14— engaging rod —12—; and it is these angle bars that rest on shelf support members —9— and —10— when the shelf is in normal use. When not in use shelf —11— folds down to a position parallel with the stiles as shown in Fig. 3 and Fig. 4.

For the re-enforcement of step ladder legs —15— and —16— we provide U shaped plates —17— and —18— held into engagement with these step ladder legs at the joint connection between the legs and stiles of the step ladder and are held substantially by square shanked 50 bolts fitting into square central holes of the U shaped plates —17— and —18— while the bolts are pivotally secured to the stiles in a manner permitting the bolt to turn in the stile as it holds to plates —3— and —4— and 55 not turn in the leg. Thus the joint is protected for a minimum of wear of the contacting movable parts.

The steps of the step ladder may be made 60 flat as shown in the drawings with reference to numeral —19— or they may be made of any other suitable material and design.

Bolt —20— snugly extends through a leg and a stile of the ladder while nut —21— may be substantially riveted on to prevent 95 the loss of the bolt.

Certain minor details of our step ladder joint and shelf support may be changed somewhat without departing from the spirit and scope of our invention but the essential char- 100

acteristics have been herein above described, are illustrated in the drawings and are hereinafter recited in the claims.

Having thus described the nature of our invention what we claim is:

- 5 1. In combination with a stepladder having spaced parallel stiles, a pair of parallel bracing legs pivotally connected with the stiles and a top shelf pivotally supported between the top end of the stiles, a pair of stepladder joints and shelf supports each respectively engaging the inner face adjacent the top end of said stiles; said joints each being formed in the shape of a Z-bar section with its outer angle engaging the forward edge of the stile and its inner angle extending inwardly toward the opposite stile; said joint members each provided with a pair of bolt holes, a bolt secured through one of said holes and through 10 the corresponding stiles and a rod pivotally supporting said shelf between said stiles and extending through the remaining hole in each of said joints and through each of said stiles where it is firmly secured into operative position; said inner angle of each of said joints being adapted to provide supporting means for said shelf when the same is in normal use.
- 15 2. In a stepladder having stiles and supporting legs pivoted thereto a pair of step-ladder joints each respectively engaging the inner face and forward edge of the stile; said joints each being formed in the shape of a Z-bar and provided with a pair of spaced bolt holes, a bolt securing each of said joints to said stile respectively through one of said holes in each joint and a relatively long rod extending through both of said stiles and through both of said joints; said joints each 20 having an inwardly extending integral plate portion adjacent its upper end; and a pivotally mounted shelf secured to said rod and adapted to be operatively supported on said inwardly extending integral plates of said joint members.
- 25 3. In witness whereof, we hereunto set our hands this 25th day of March, 1929.
- 30 SPENCER M. PETERS.
ARTHUR B. ROCHESTER.
